UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,403, dated December 16, 1890.

Application filed May 14, 1890. Serial No. 351,811. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawings, forming a part thereof.

- 10 The design relates to a clay or other tile in which the ornamental effects are produced by the outline of the tile, by the surface ornamentation thereof, and the conjunction of the two.
- 15 The design consists of a surface ornamentation formed by a conventional shell-pattern made in relief upon the surface of the tile.

It also consists in the scallop or undulating outline on the lower edges of the tile alone 20 and in conjunction with said surface ornamentation.

In the drawings, Figure 1 illustrates a face view of a tile of the design; and Fig. 2 illustrates a number of such tiles laid in quincunx 25 order, illustrating the effect of the shape or outline and the surface ornamentation of the tile when associated with other like tiles.

The design relates particularly to the ex-

posed or lower face of a tile, its upper portion partaking of various shapes.

As illustrated, the tile has diagonal upper sides *a a*, which bear upper flanges. The lower or exposed portion of the tile *A* is substantially flat, which, however, is provided with a series of lobes or corrugations *B*, resembling in conventional character the surface of a scalloped bivalve-shell. The lobes or corrugations *B* commence at a point *c* at the upper part of the exposed face of the tile and diverge therefrom in oppositely-curved 40 lines terminating around the bulbous ends *d*, with which the contour or outline of the edge of the tile is made to form the undulated lines *e*. The bulbous ends *d* of the center lobe or corrugation *B* terminate in an angular contour or point and the undulating line in a corresponding point, as shown in the drawings, relieving the similarity of the curves.

What is claimed is—

The design for a tile, substantially as described and shown.

GEO. H. BABCOCK.
